POR TABLE THEFTPROOF BOX

Filed May 5, 1926

UNITED STATES PATENT OFFICE.

NATHAN UROVSKY, OF NEW YORK, N. Y.

PORTABLE THEFTPROOF BOX.

Application filed May 5, 1926. Serial No. 106,923.

The present invention is concerned with the provision of a portable receptacle in the nature of a box adapted to be used by messengers when carrying cash, securities, or other negotiable instruments, or valuables.

An object of the invention is to provide a device of this character, so constructed that the owner of the contents of the box is protected, not only against the possibility of the messenger being held up and robbed, but against dishonest messengers as well.

In a preferred embodiment of the invention, the box is actually locked to the messenger's body in such a manner that the box cannot be detached from the body without the use of the proper keys. Preferably means is provided for actually handcuffing the messenger and a guard or companion to the box, so that the only way in which a bandit could rob the messenger and his companion would be to carry them and the box away bodily. Obviously the ordinary bandit would not have time to forcibly break into the box or remove it from the messenger's body without being apprehended. Obviously also, there is little chance of there being collision between the messenger and his companion, both of whom are padlocked to the box.

Further objects of the invention are to provide a box of the above described character which will be of simple practical construction, which will be rugged and durable in use, and which may be manufactured with comparative economy.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a perspective view showing a box embodying the present invention in closed position.

Fig. 2 is a perspective view showing the two box sections swung apart and exposing the mechanism at the interior of the box.

Fig. 3 is a vertical sectional view through the box indicating in dotted lines the position of a messenger's hand when the box is being carried.

Fig. 4 is a detail elevational view of the interior mechanism of the box.

The box may be made of any suitable material which will resist attempts to forcibly crush the walls or pry the same open. As in the case of most boxes which are designed for housing cash or securities, it is preferably made of strong sheet metal including a pair of relatively shallow tray-like sections 10 and 11 hingedly connected at one edge by suitable hinges 12. The free edges of the sections 10 and 11 meet at the top of the box, and are provided with opposed mating recesses 13, defining an opening through which the hand of a messenger indicated in dotted lines in Fig. 3, is inserted. Staples 14 on the box section 11 are adapted to be engaged by hasps 15 carried by the section 10, and suitable padlocks (not shown) may be passed through the staples after the hasps are swung down over them.

Additional locks may be provided at the interior of the box. I have shown key actuated bolts 16 on the section 11 adapted for coaction with keepers 17 on the section 10, the bolts being operated by keys (not shown) entered into keyholes 18 at the exterior of the section 11.

At the interior of the box there is provided a horizontal partition 19 carried by the section 10 and adapted to extend the full width of both box sections when the box is closed. Rising from the partition 19 are a pair of vertical partitions 20 which extend approximately to the top of the box, and mount between them a handle 21 adapted to be grasped by the hand of the messenger inserted through the opening 13.

The box may be provided with a shoulder strap 22 to be swung over the messenger's shoulder and aid in supporting the weight of the box, and the section 11 may carry at one side a handle 23 to be grasped by the messenger's companion who may assist in carrying the box.

Firmly anchored in the compartment defined between the two vertical partitions 20 is a strap 24. This strap may be conveniently connected to a staple 25, and at one end carries a handcuff 26 adapted to encircle the wrist of the messenger grasping the handle 21. Mounted on the exterior of the box, and anchored as to a staple 27 is another strap or chain 28 carrying a handcuff 29 which may be conveniently clamped about the wrist of the messenger's companion whose hand is grasping the handle 23.

In operation, the securities or cash to be

carried may be placed in the lower portion of the box beneath the partition 19. The messenger grasps the handle 21 and has his wrist handcuffed before the box is closed about his wrist. The box is then closed and locked by the use of the bolts 16 and padlocks on the staples 14. The strap 22 may be swung over his shoulder and an attendant or companion to the messenger may grasp the handle 23 and have his wrist locked by the handcuff 29.

The messenger and his companion are thus both padlocked to the box which houses the valuables, and it would be practically impossible to effect robbery of the messenger, unless there is collusion between both the messenger and his companion. The ordinary bandit or holdup man could not attack the messenger forcibly, release the box from his body, and open the box without being apprehended, since the time factor necessarily enters into all attempts at such holdups.

Means may be additionally provided for the messenger's sounding an alarm in case of an attempted holdup. With this end in view I mount a bell or other audible alarm signal 30 on the partition 19, together with a battery 31 for energizing the bell circuit. A spring 30 pressed switch 32 for closing the circuit carries an operating finger 33 within convenient reach of a finger of the messenger grabbing the handle 21, so that the alarm circuit may be selectively sounded at any time.

In many instances the use of the handcuff 26 may be dispensed with, since this handcuff is merely designed to prevent the retraction of the messenger's hand. If the hand and wrist of the messenger are large enough, the opposed recesses 13 in the box top will serve as an effective handcuff.

Obviously various changes and alterations might be made in the general form and arrangement of parts described without departing from the invention. Hence I do not wish to limit myself to the detail set forth, but shall consider myself at liberty to make such changes and alterations as fairly fall

within the spirit and scope of the appended claims.

50

I claim:

1. A portable theft-proof box including a pair of hinged sections having aligned recesses in their free edges cooperatively defining and opening when the box is closed which is adapted to encircle the wrist of one carrying the box and prevent the retraction of the hand therefrom, and a handle on the interior of the box adapted to be manually grasped.

60

2. A portable theft-proof box including a pair of hinged sections having aligned recesses in their free edges cooperatively defining an opening when the box is closed which is adapted to encircle the wrist of one carrying the box and prevent the retraction of the hand therefrom, a handle on the interior of the box adapted to be manually grasped, and means for locking the hinged sections together whereby the hand of the carrier is locked in the box.

65

3. A portable theft-proof box including a pair of hinged sections having aligned recesses in their free edges cooperatively defining an opening when the box is closed which is adapted to encircle the wrist of one carrying the box and prevent the retraction of the hand therefrom, a handle on the interior of the box adapted to be manually grasped, means for locking the hinged sections together whereby the hand of the carrier is locked in the box, and a handcuff anchored inside of the box and adapted to encircle the carrier's wrist within the box.

75

4. A portable theft-proof box including a pair of hinged sections having mating recesses in their free edges, a horizontal partition in the box and vertical partitions between the horizontal partition and the box top, a handle mounted between the vertical partitions and adapted to be grasped by the hand of a carrier when the carrier's wrist is locked in the opening defined by the mating recesses.
